UNITED STATES PATENT OFFICE.

WALTER LORD LE MAITRE, FREDERIC GEORGE WILLIAM PARKER, AND EDGAR RHODES, OF LEEDS, ENGLAND.

APPLIANCE FOR CUTTING OFF THE UPPER OR WEARING PORTIONS OF COMPOUND TRAMWAY-RAILS.

SPECIFICATION forming part of Letters Patent No. 718,362, dated January 13, 1903.

Application filed July 22, 1902. Serial No. 116,497. (No model.)

To all whom it may concern:

Be it known that we, WALTER LORD LE MAITRE, FREDERIC GEORGE WILLIAM PARKER, and EDGAR RHODES, subjects of the King of Great Britain and Ireland, residing at Greek Street Chambers, Leeds, in the county of York, England, have invented a certain new and useful Appliance for Cutting Off the Upper or Wearing Portions of Compound Tramway-Rails, (for which we have made application for a patent in Great Britain, No. 9,176, bearing date April 21, 1902,) of which the following is a specification.

This invention relates to a new or improved appliance for cutting off the upper or wearing portions of compound tramway-rails on the same becoming worn out in a speedy and efficient manner, and this without disturbing the base or foundation portions of the rails.

The appliance consists, essentially, of a carrying-frame provided with supporting-rollers which engage the upper surface of the compound rail, and the said frame is also provided with roughened or serrated guide-rollers, which are so rotated in contact with the sides of the upper or wearing portion of the rail as to cause the carrying-frame to travel thereon. The frame carries a series of disk cutters, which are so located as to engage one of the flanges of the upper portion of the rail, and the said cutters are mounted in adjustable sliding bearings and are so operated as to cut into and sever the engaged flange of the compound rail.

In the drawings, Figure 1 is an elevation, partly in section, of an appliance constructed according to our invention applied to a compound tramway-rail; and Fig. 2 is a plan view of the same appliance and rail. Fig. 3 shows in side elevation, to a reduced scale, an example of the general application of our appliance to compound tramway-rails.

Referring to the drawings, 1 represents the carrying-frame of the appliance, provided with supporting-rollers 2 2 2 2, whose bearings are attached to screwed studs 3 3 3 3, through the medium of which the said rollers may be adjusted in height. The frame 1 is also provided with guide-rollers 4 5 6, which are mounted on tubular shafts 7 8 9, and through these tubular shafts are fitted studs

10 11 12, on the lower ends of which are mounted auxiliary guide-rollers 13 14 15, which latter are free to revolve on their respective studs 10 11 12. The guide-rollers 4 5 6 and 13 14 15 are serrated or roughened on their periphery, and the studs 10 11 12 are screwed at their upper ends and provided with nuts 16 17 18, whereby the said studs may be raised or lowered in their tubular shafts 7 8 9 60 in order to adjust the height of the auxiliary rollers 13 14 15. The tubular shaft 7, carrying the stud 10 and guide-roller 4, is mounted in an eccentric bearing 19, provided with an arm 20, and on the frame 1 is fixed a bracket 65 21, provided with a set-screw 22, which latter engages the arm 20 of the bearing 19 to operate the latter, and so vary the position of the roller 4 as desired.

On the frame 1, at one side thereof, are located steel disk cutters 23 24 25, mounted in sliding bearings 26 27 28, and set-screws 29 30 31 are employed, respectively, in connection with the said bearings, whereby the cutters 23 24 25 may be adjusted in a forward direction at will.

On the tubular shaft 9 of the roller 6 is mounted a spur-wheel 32, which is driven by a spur-pinion 33, carried on a shaft 34, which latter is driven by suitable speed-gearing, as 80 hereinafter described, whereby the said roller 6 is caused to rotate.

The appliance is mounted upon a face-plate 35 of a traveling bogie 36, the said face-plate having slots 37, provided with T-headed bolts 85 38, which pass through a projecting flange 39, formed on the back of the carrying-frame 1, whereby the latter is secured in position.

The bogie 36 in addition to carrying the appliance carries a motor for driving the shaft 90 34, consisting of a boiler 40 and an engine 41, which latter is provided with a driving-shaft 42, extending across the front of the bogie 36 and being carried in end bearings 43, attached to the platform of the said bogie. On 95 the driving-shaft 42 is mounted a sprocket-wheel 44, which, through the medium of a chain 45, drives a sprocket-wheel 46, located on a stud 47, carried by a bearing 48, situated on the frame 1 of the appliance, and the 100 said stud 47 also carries a worm 49, which gears with a worm-wheel 50, mounted on the

shaft 34, whereby the desired rotary motion is imparted to the gear-wheels 32 33 and serrated rollers 6 and 15.

The operation of cutting off the upper or 5 wearing portions of compound tramway-rails is as follows: The bogie 36 is placed upon the rails, which latter consist of upper or wearing portions 51 and their base or foundation portions 52, the appliance being located 10 over one of the rails, with its supporting-rollers 2 2 2 2 resting upon the upper surface of the rail and the guide-rollers 4 5 and auxiliary guide-rollers 13 14 located on one side of the rail and the guide-roller 6 and auxiliary 15 guide-roller 15 on the other side thereof. The engine is now put in motion, whereby the geared roller 6 is caused to revolve through the medium of the speed-gearing above described, when the set of rollers 4 5 6 are forced tight 20 onto the upper sides of the rail by rotating the eccentric bearing 19 of the roller 4 through the medium of the set-screw 22, while the auxiliary guide-rollers 13 14 15 are set up to the flanges of the upper portion 51 of the rail 25 by adjusting the height of the studs 10 11 12 through the medium of the nuts 16 17 18, after which the disk cutters 23 24 25 are fed into the side or flange of the upper or wearing portion 51 of the rail by means of the set-screws 30 29 30 31. The rollers 4 5 6, by reason of their grip or frictional contact on the rail, cause the bogie 36, with its appliance, to travel along the rails, when the cutters 23 24 25, which are fed forward in step-like order, cut into and sever 35 the flange of the wearing portion 51 of the rail, and this without disturbing the base or foundation portion 52. After one of a pair of rails has been treated in the manner above described the appliance may be transferred 40 across the face-plate 35 of the bogie 36 into position to operate upon the other rail, or, if desired, the bogie 36 may be fitted with two cutting appliances of the above-described construction, one for each rail, whereby the top 45 portions of both rails may be cut through simultaneously.

Having now described our invention, what we claim as new, and desire to secure by Letters Patent, is—

50 1. An appliance for the purpose specified, comprising a carrying-frame provided with supporting-rollers arranged to engage the up-

per surface of the rail, a set of serrated or roughened guide-rollers situated so as to cause them to grip the sides of the rail, and a series 55 of disk cutters so located and operated as to cut into and divide the upper portion of the rail longitudinally into two parts, substantially as described.

2. An appliance for the purpose specified, 60 comprising a carrying-frame provided with supporting-rollers mounted in adjustable bearings, a set of serrated or roughened guide-rollers located on carrying-studs, a series of disk cutters mounted in adjustable sliding 65 bearings, means for adjusting the serrated guide-rollers up to the sides of the rail and mechanism for rotating the said guide-rollers, substantially as described.

3. An appliance for the purpose specified, 70 comprising a carrying-frame provided with supporting-rollers mounted in adjustable bearings, a set of serrated or roughened guide-rollers mounted on tubular shafts carried upon adjustable studs provided with auxiliary 75 guide-rollers, a series of disk cutters mounted in adjustable bearings, means for adjusting the serrated guide-rollers up to the sides of the rail and mechanism for rotating the said guide-rollers, substantially as described. 80

4. An appliance for the purpose specified, comprising a carrying-frame provided with supporting-rollers, a set of serrated or roughened guide-rollers located on carrying-studs, a series of disk cutters mounted in adjustable 85 sliding bearings, means for adjusting the serrated guide-rollers up to the sides of the rail, speed-gearing in connection with one of the guide-rollers, a flange formed on the carrying-frame provided with fixing-bolts which 90 engage a face-plate of a traveling bogie arranged to run on the rails, and a motor on the said bogie provided with a driving-shaft connected with the speed-gearing of the guide-roller, substantially as described. 95

In witness whereof we have hereunto set our hands in presence of two witnesses.
